UNITED STATES PATENT OFFICE.

MILES H. BICKELHAUPT, OF UTICA, NEW YORK.

FIGURE TOY.

1,210,266.

Specification of Letters Patent. Patented Dec. 26, 1916.

Application filed August 16, 1916. Serial No. 115,307.

To all whom it may concern:

Be it known that I, MILES H. BICKELHAUPT, a citizen of the United States, residing at Utica, in the county of Oneida and State of New York; have invented new and useful Improvements in Figure Toys, of which the following is a specification:

This invention relates to toys and it consists in the novel features hereinafter described and claimed.

An object of the invention is to provide a toy of simple and relatively durable structure which comprises a body portion and arms pivotally attached thereto. The toy is in the general figure of a grotesque man and one leg is fixed with relation to the body and the other leg pivotally connected therewith. A spring connects the inner ends of the legs together whereby the inner portion of the 15 pivot leg is normally held toward the inner portion of the fixed leg. Links are pivotally connected with the pivot leg and the arms whereby the arms are caused to swing when the pivot leg is swung with 20 relation to the fixed leg. A rod is pivoted at the back of the toy and arranged to swing over the head of the figure. The said rod is provided with an angularly disposed end adapted to engage the free end portions of 25 the arms whereby the said rod is swung over the head of the figure. In one form of the invention a body simulating a club is attached to the arm or pivoted thereon and may swing upon the arm as the arm swings 30 over the head of the figure. In another form of the invention bodies are attached to two rods which have appearance of balls juggling when the arms manipulate the rod.

In the accompanying drawings:—Figure 40 1 is a perspective view of the toy. Fig. 2 is a front view thereof with parts removed. Fig. 3 is a top view of the same. Fig. 4 is a front view of a modification with parts removed. Fig. 5 is a top view of the toy 45 as shown in Fig. 4. Fig. 6 is a side view of a modified structural detail.

As hereinbefore stated the toy is in the form of a grotesque figure and its body comprises a back plate 1 and a front plate 2. A fixed leg 3 is positioned between the front and back plates and a pivot leg 4 is also positioned between the said plates. A spring 5 is connected with the upper or inner ends of the said legs and is under tension with a tendency to hold the upper portion of the pivot leg toward the upper end of the

fixed leg. Hook blocks 6 are mounted at the lower ends of the legs 3 and 4 and the blocks are of sufficient size to permit the figure to stand direct upon a level surface. A 60 head block 7 is secured between the upper ends of the front and back plates 1 and 2. A face of any suitable character may be painted or otherwise applied to the head block 7. Arms 8 are pivoted between the 65 upper ends of the plates 1 and 2 at the shoulder portions of the figure and links 9 are pivotally connected at one end with the said arms and pivotally connected at their other ends with the upper portion of the 70 pivot leg 4. As shown in Fig. 2 of the drawing the upper end of one link 9 is pivoted below the pivot of one of the arms and the upper end of the other link 9 is pivoted above the pivot of the other arm. Consequently when the pivot leg 4 is swung 75 with relation to the fixed leg 3 the links 9 are moved longitudinally whereby one arm 8 swings in an upward direction and simultaneously the other arm 8 swings in a downward direction and vice versa. A rod 10 is pivoted to the back plate 1 and the lower portion of the head 7 of the figure and the said rod is provided at its upper end with a forwardly disposed extremity 11 which is 80 disposed transversely across the paths of movement of the arm 8. A club 12 is pivoted upon the extremity 11 of the rod 10. Consequently it will be seen that as the arms are swung as hereinbefore indicated they 85 alternately strike the extremity 11 of the rod 10 whereby the said rod is swung and the said extremity is carried over the figure head 7 of the toy. After the extremity 11 leaves one arm it strikes the other arm and inasmuch as the said arms are swung alternately the said extremity swings back and forth over the head of the figure. In view of the fact that the club 12 is pivotally mounted upon the extremity 11 the said club 90 swings during the swinging movement of the arm and simulates the swinging of an Indian club.

In the form of toy as shown in Fig. 4, 105 two rods 10 are employed and the said rods are pivotally connected with the back plate and head block of the figure. The last mentioned rods are also provided with forwardly disposed extremities similar to the extremity 11 hereinbefore described and the links 9 are so connected with the arms 8 that the said arms swing simultaneously in an 110

upright direction and simultaneously in a downward direction. The rods 10 are separated so that the extremity of one rod bears against the upper edge of one arm and the 5 extremity of the other rod bears against the upper edge of the other arm. Consequently as the arms move in an upright direction the rods are moved from one arm to the other across the upper portion of the head 10 of the figure. The said extremities are provided with blocks 13 which simulate balls and consequently the toy as shown in Fig. 4 when operated has the appearance of a figure juggling the balls in a path over the 15 head of the figure.

The inner portions of the legs 3 and 4, the inner portions of the arms 8 and the front and back plates 1 and 2 are covered by a suit 14 made of any appropriate material and preferably simulating a suit worn 20 by a clown.

From the foregoing description taken in connection with the accompanying drawing, it will be seen that a toy of simple and 25 durable structure is provided and the same includes attractive features inasmuch as the arms are caused to move to give the toy the

appearance of swinging a club or juggling balls according to the arrangement of the rods mounted on the body thereof.

30

Having described the invention what is claimed is:—

1. A toy in the form of a figure having a body portion, a leg fixed with relation to the body portion, a leg pivoted to the body portion, a spring connecting the legs together, arms pivoted to the body portion, links connecting the arms with the said pivoted leg, a rod pivoted to the body portion and having an angularly disposed end located in the 35 path of movement of the said arm.

2. A toy in the form of a figure having a body portion, a leg fixed to the body portion, a leg pivoted to the body portion, a spring connecting said legs together, arms 45 pivoted to the body portion, links pivotally connecting the arms with the pivoted leg, a rod pivoted to the body portion and having an angularly disposed extremity located in the path of movement of the arms and a 50 club pivoted on said extremity.

In testimony whereof I affix my signature.

MILES H. BICKELHAUPT.
